UNITED STATES PATENT OFFICE.

JAMES FRANCIS HERBERT COLLET, OF DULWICH, ENGLAND.

APPARATUS FOR RECORDING THE MOVEMENTS OF LOCOMOTIVES, VEHICLES, OR MACHINERY.

No. 835,901.

Specification of Letters Patent.

Patented Nov. 13, 1906.

Application filed March 31, 1905. Serial No. 253,104.

To all whom it may concern:

Be it known that I, JAMES FRANCIS HERBERT COLLET, a subject of the King of Great Britain and Ireland, residing at 296 Lordship Lane, Dulwich, in the county of Surrey, England, have invented certain new and useful Apparatus for Recording the Movements of Locomotives, Vehicles, or Machinery, of which the following is a specification.

10 My invention relates to recording apparatus for indicating the rate of speed, the direction of travel, and the periods of rest of locomotives, motor-cars, tramway or other vehicles, or machinery, my object being to 15 produce a simple and efficient apparatus capable of recording in a permanent manner both the duration and the character of the movements made by the locomotive, vehicle, or machine to which the apparatus is applied.

20 In the accompanying drawings, which illustrate a recording apparatus constructed according to my invention, Figure 1 is a face view, Fig. 2 a plan, and Fig. 3 an end view, of the apparatus. Fig. 4, is a vertical section on 25 the line $z-z$ in Fig. 1, showing the paper-support and the operating-disk; and Fig. 5, a rear view of the roller on which the record is wound. Fig. 6 illustrates, to an enlarged scale, the cam for operating the marker; and 30 Fig. 7, a portion of a record indicating the movements of a locomotive.

In apparatus constructed according to my invention I employ an ordinary clock A; but in place of the hands is mounted a disk a , 35 whereof the periphery is furnished with a series of pins a' , adapted to engage in holes b , formed in the edge of a strip of paper B. This strip of paper is preferably marked with a series of transverse arcs representing equal 40 intervals of time. As the disk a rotates the strip of paper B, which is supported partly upon the pin-disk a and partly upon a platform b' , becomes unwound from a roller C, mounted upon the frame of the apparatus, 45 and wound upon a roller D, mounted upon a rocking arm d' , the platform b' serving to support the strip of paper in its passage from the feed-roller to the gathering-roller. The roller D is supported upon a pin d , secured to 50 the arm d' , which in turn is pivotally mounted on the frame of the apparatus at d^4 , a spring d^2 operating to maintain the roller D in frictional contact with the edge of the rim a^2 of the disk a . The disk a rotates the roller 55 D by reason of the frictional contact before

referred to, an arm d^3 being pivotally mounted on the frame above the roller D in such a manner that its free end rests upon the roller and prevents backlash. A bell-crank spring-lever E is pivotally mounted upon a bracket e 60 at e^{15} , attached to the frame of the apparatus, and is furnished at its free end with a pricker or striker e' for making the record upon the paper B, the said pricker being moved in a direction transverse to the movement of the 65 paper.

For operating the lever E in a horizontal plane a cam e^2 is employed, the latter bearing against an arm e^{12} , arranged at a right angle to the lever E. For driving the cam e^2 a 70 spur-gear train $e^3 e^4 e^5$ is employed, the spindle e^{10} of the pinion e^5 being operated by a worm-wheel e^9 and worm e^8 . It is assumed that the worm-wheel shaft e^7 is driven from some working part of the machine, the movements of which are to be recorded. 75

For operating the lever E in a vertical plane a tappet e^{11} is secured upon the front end of the spindle e^{10} , the said tappet periodically bearing against the spring-lever E 80 in such a manner as to lift it and then suddenly to release it with a view to causing the pricker or striker e' , carried at the free end of the resilient lever, to prick or strike the paper strip B, so as to produce a perforation therein 85 or an impression thereon and then instantly to spring clear of the paper. These perforations or impressions furnish the desired record of movement, and owing to the traversing action of the lever the pricker or striker will not strike the paper strip twice in the same spot. A slot b^2 is formed in the platform b' in order to permit the pricker to pass through the paper.

The cam e^2 , which operates the bell-crank 95 lever E, engages the arm e^{12} beyond the pivot of the lever, and the cam is so shaped that the lever is gradually moved in the one direction while recording the movements of the machine and then under the influence of the 100 spring e^{14} is caused to return quickly in the interval between two consecutive perforations. By operating the lever E in this manner the record holes or impressions are in a series of lines more or less parallel instead of in 105 a zigzag line, as would be the case if the lever moved at an equal speed to and fro across the paper. The cam e^2 is, moreover, shaped in such a manner as to admit of its being rotated in either direction, the lines of perfora- 110

tions formed in the paper strip being inclined in the one direction or in the other according to whether the cam e^2 be rotated in one direction or in the other.

- 5 The tappet e^{11} is preferably provided with rocking extremities e^{13} with a view to facilitating the sudden release of the spring-lever E in either direction of rotation of the tappet.

The pin-disk a, which drives the paper strip, may be mounted to rotate freely on its spindle like the minute-hand of a clock. Although while driving the paper strip it is in operative connection with the spindle by friction or an adjustable clamp, it can also be 15 rotated independently of the spindle when it is required to set the paper to the actual time of day. In the diagram Fig. 7 the large figure stands for hours and the small figures for minutes.

- 20 The interpretation of the diagram is as follows: Assuming the distance between any two of the transverse lines to represent the travel of the paper strip during half a minute and assuming the distance between any two 25 adjacent perforations to represent a previously-fixed distance (such as fifty yards) traversed by a locomotive to which the apparatus is applied, it will be seen that shortly before ten o'clock the engine started and 30 moved forward about a quarter of a mile, from f to f' . It then immediately reversed and moved backward for about the same distance, f' to f^2 . Again reversing, it moved forward for about a mile, f^2 to f^3 , and then 35 moved backward for about three furlongs, gradually slowing down till it stopped at f^4 . The locomotive after waiting about three minutes started forward again at f^5 , going slowly at first and then gradually increasing 40 in speed to f^6 it traveled at an accelerated speed about sixty miles an hour to f^7 , when

the speed was quickly reduced to about sixteen miles an hour.

What I claim as my invention, and desire to secure by Letters Patent, is—

45 1. In apparatus for recording the movements and the speed of locomotives, tramway, and other vehicles or of machinery, the combination of a pivotally-mounted bell-crank lever furnished with a pricker at its free extremity, a cam for vibrating said lever in a horizontal plane, a tappet for vibrating the lever in a vertical plane, and means for operating said tappet and cam from the engine or machine the speed or movements of 50 which are to be recorded, substantially as herein described.

55 2. In apparatus for recording the movements and the speed of locomotives, tramway and other vehicles or of machinery, 60 same being provided with a strip of paper marked to represent certain intervals of time, the combination, with clockwork mechanism, of a pin-wheel engaging said paper strip and driven by said clockwork, a platform for 65 supporting said paper strip, a marker or pricker arranged above said paper and attached to the free extremity of a pivotally-mounted bell-crank lever, a cam for vibrating said lever in a horizontal plane, a tappet 70 for vibrating said lever in a vertical plane, and means for operating said cam and tappet from the engine, the speed or movements of which are to be recorded, substantially as herein described.

75 In testimony whereof I have signed my name to this specification in the presence of two subscribing witnesses.

JAMES FRANCIS HERBERT COLLET.
